J. H. L. EAGER.

SYRINGE,

APPLICATION FILED JULY 1, 1916.

1,243,054.

Patented Oct. 16, 1917.

UNITED STATES PATENT OFFICE.

JAMES H. L. EAGER, OF NEW YORK, N. Y.

SYRINGE.

1,243,054.

Specification of Letters Patent.

Patented Oct. 16, 1917.

Application filed July 1, 1916. Serial No. 107,041.

To all whom it may concern:

Be it known that I, JAMES H. L. EAGER, a citizen of the United States, residing at New York, in the county of Kings, State of New York, have made a certain new and useful Invention in Syringes, of which the following is a specification.

The invention relates to syringes, and more particularly to that class known as water bag syringes and in which a pressure seat is used which rests upon the bag, the weight of the person using the syringe causing the water or other cleansing fluid to be forced from such bag and through an injection nozzle to the part to be treated.

The object of the invention is to provide a syringe of the class described including an improved type of pressure seat and fluid control device.

20 Further objects of the invention will appear more fully hereinafter.

The invention consists substantially in the construction, combination, location and relative arrangement of parts, all as will be more fully hereinafter set forth, as shown by the accompanying drawing, and finally pointed out in the appended claims.

Referring to the drawing:—

Figure 1 is a top plan view of a syringe embodying my invention.

Fig. 2 is a side view of the same.

Fig. 3 is a sectional view taken on the line 3—3, Fig. 1, looking in the direction of the arrows.

35 Fig. 4 is a view in section, taken on the line 4—4, Fig. 2, and looking in the direction of the arrows.

The same part is designated by the same reference numeral wherever it occurs throughout the several views.

Reference numeral 5 designates the usual form of water bag made of rubber or rubber cloth having a screw threaded filling opening 6. I provide a pressure seat 7 of any suitable material, preferably of rubber or rubber cloth extending substantially over the entire surface of the bag 5. The upper surface of the bag 5 is provided with an opening 8 formed with upwardly extending walls 9 provided with internal screw threads as shown best in Fig. 3. A nozzle 10 of any desired material, preferably of some soft composition such as rubber, screws into the opening 8 or the opening 6. The pressure seat 7 is split as at 11, and is provided with

a flared portion 12 which embraces the neck 9. Secured to edges of the pressure seat 7 and pivotally secured to each other as at 13 are two pressure tongs 14, 15, which when pressed tightly together securely pinches the 60 walls 8 together and prevents further flow of the fluid from the bag through the nozzle, as shown best in Fig. 4. The tongs may be held together in their pinched position in any suitable manner, as, for example, 65 by the well known form of latch device 20 which is pivotally connected to the tong 15 and adapted to slip over the tong 14.

It is obvious that by the mere manipulation of the tongs 14 and 15, the fluid from 70 the bag can be readily controlled.

It is obvious that when the syringe is adjusted for use, the weight of the body of the user on the pressure seat, will cause the water or fluid contained in the bag to flow 75 through the nozzle to the part or parts to be treated.

Having now set forth the object and nature of my invention, and having shown and described a structure embodying the 80 principles thereof, what I claim as new and useful and of my own invention and desire to secure by Letters Patent, is—

1. A syringe comprising a water bag provided with a neck, a pressure seat adapted 85 to rest on said bag, and to surround said neck, and means carried by said pressure seat for pinching said neck to control the supply of fluid from said bag through said neck.

2. A syringe comprising a water bag provided with a neck adapted to receive a nozzle therein, a pressure seat adapted to rest on said bag and to surround said neck, and means carried by said pressure seat for 95 pinching said neck to control the supply of fluid from said bag to said nozzle.

3. A syringe comprising a water bag provided with a neck adapted to receive a nozzle therein, a pressure seat adapted to rest 100 upon said bag and split a substantial distance through its center, to allow the same to surround said neck, and tongs carried by the respective sides of the split pressure seat and pivotally connected to each other, 105 for controlling the supply of fluid from said bag to said nozzle.

4. A syringe comprising a water bag provided with a neck adapted to receive a nozzle therein, a pressure seat adapted to rest 110

upon said bag and split a substantial distance through its center, to allow the same to surround said neck, and tongs carried by the respective sides of the split pressure seat and pivotally connected to each other, and adapted, when pressed together to pinch said neck to prevent communication be-

tween said bag and said nozzle, and means carried by said tongs for locking the same in their closed position.

10

In testimony whereof I have hereunto set my hand on this 27th day of June, A. D. 1916.

JAMES H. L. EAGER.
